UNITED STATES PATENT OFFICE.

WILLIAM BARSBY, OF KING'S HEATH, COUNTY OF WORCESTER, ENGLAND.

LOCK-STITCH SEWING-MACHINE.

SPECIFICATION forming part of Letters Patent No. 313,705, dated March 10, 1885.

Application filed December 5, 1884. (No model.) Patented in England February 1, 1884, No. 2,529.

To all whom it may concern:

Be it known that I, WILLIAM BARSBY, of King's Heath, in the county of Worcester, England, a subject of the Queen of Great Britain, have invented Improvements in Lock-Stitch Sewing-Machines, (for which I have obtained a patent in Great Britain, No. 2,529, bearing date February 1, 1884,) of which the following is a specification.

10 My invention has for its object improvements in lock-stitch sewing-machines; but is more especially applicable to those machines designed for sewing heavy material—such, for instance, as leather—and where there is considerable difficulty in piercing the material from one side, or where, because of the several thicknesses of material to be sewed, the bulging at the under side would be considerable when pierced from the top only. I am also able to 15 insure great regularity of work, because there is less strain upon the weak parts of the machine, and therefore the work is better in quality, without leaving the marks of the feeding-piece, which is usually the case.

20 The invention belongs particularly to that type of wax-thread sewing-machines which employ an awl or piercer and a needle, the awl being so arranged on the bed-plate as to feed the material to be sewed along said table after 25 the performance of each piercing operation.

The invention consists in a novel construction and arrangement of said awl and feeding device, and in the means for imparting a vertical and horizontal movement to the same, 30 all as will be hereinafter more fully described, and then set forth in the claims.

In the drawings, Figure 1 represents in front elevation, Fig. 2 in side elevation, and Fig. 3 in plan, a portion of a lock-stitch sewing-machine containing my improvements. Fig. 4 is a plan of the shuttle-box of the machine. Fig. 5 represents separately the piercer and feeder of the machine, made preferably of steel, and Fig. 6 a modification of the said 45 piercer and feeder, the said Figs. 5 and 6 being drawn of the full size. Figs. 7 and 8 represent a modified construction of parts for operating the awl and feeding device.

The same letters indicate the same parts in the several figures of the drawings, wherein I have illustrated so much of a wax-thread

sewing-machine as is necessary to show the adaptation of my improvements.

a is the fixed base of the machine. *b* is the shuttle-box. *c* is the needle, and *d* the pressure-foot for holding down the material during the sewing operation. *e* is the plate piercer and feeder, made according to my invention, the said plate being of such thickness that it will move freely in the needle-groove *f*, made in the needle-plate, and the shuttle-box *b* for the passage of the needle. (See Figs. 1 and 4.) The said piercer *e* pierces the material from the under side, and acts also as a feeder, as hereinafter explained. The shape of the piercer *e* is best seen in Figs. 2 and 5, and from an examination of the said figures it will be seen that the piercer has a sharp or pointed end, and owing to its great depth is rigid up to its working-point. The plate piercer and feeder *e* is fixed in the slotted end of the holder *g* by the screw *h*. This holder is fitted in the vertical carrier *i*, in which it is capable of rising and falling. The said carrier *i* is connected to the dovetail plate *i*², capable of a horizontal sliding motion in the base-plate *a* of the machine. (See Fig. 1.) The said dovetail plate *i*² works between the stop-screws *i*³ *i*⁴. (See Figs. 2 and 3.) The length of stitch is regulated by the screw *i*⁵ in front of the machine. The rising and falling motion of the piercer and feeder *e* is effected by the lever *k*, pivoted at one end, *l*, to the fixed upright *m* on the sliding plate *i*², and connected at its other end by the pin *n* to the sliding holder *g*, supporting the piercer *e*. The end *k*² of the lever *k* is slotted, to permit it to work upon the pin *n*. The rocking motion of the lever *k* upon the center *l*, by which it communicates a rising and falling motion to the holder *g*, is effected by the cams *p* and *q* on the driving-shaft *s* of the machine, the said cams working in the box or slotted part *k*³ of the lever. The rising motion of the lever is effected by the cam *q* and the descending motion by the cam *p*. The advance or feeding motion of the piercer, so as to feed forward the material being sewed, is effected by the cam *r* on the shaft *s* acting against the bearing-stop *t* on the upright *m* of the base-plate *i*², 95 the return motion of the said base and parts carried by it being effected by the coiled

spring u , one end of which is connected to the dovetail plate v , and the other end to the fixed base a of the machine. The feeding-stop t is made adjustable to compensate for wear in the cam r , and to insure that the piercer e at the end of its feeding movement shall be exactly under the needle. The stop t is shown withdrawn beyond the range of the cam r in order that the cams may be more readily seen. The center l is capable of a slight vertical adjustment in the upright m , to enable the piercer e to pierce the material to a greater or less extent, as may be desired. A slot in the upright m , and a nut on the center l , may be resorted to for giving the vertical adjustment to the piercer.

By the arrangement of parts described the piercer e , when situated behind or on one side of the central position of the needle c , rises and pierces from the under side the leather or material being sewed. While the piercer is inserted in the leather or material its feeding or horizontal sliding motion is effected, as hereinbefore described, and the said piercer is thereby carried exactly underneath or in a line with the needle c , as represented in Fig. 2. After having pierced and fed the material to the position last described, the piercer first makes its descending motion, so as to remove it from the material, and afterward makes its back sliding motion to the length of one stitch—that is, to its original position. The needle c , descending from the upper side of the material, passes through the hole formed by the piercer e . As the needle makes its ascending motion the thread is formed into a loop on the under side of the material, and the shuttle being shot through the looped thread a lock-stitch is formed in the ordinary way. The pressure-foot d is raised while the piercer e is feeding forward the material, so as to prevent any undue strain upon the said piercer, said pressure-foot being raised in any preferred manner.

The piercer and feeder e may be connected directly to the actuating-lever, instead of to the holder g , and the said actuating-lever be worked by the modification of parts represented in side elevation in Fig. 7 and back elevation in Fig. 8. In this arrangement, 2 is the lever, to the cranked or vertical end of which the plate-piercer e is affixed by the screws e^2 . Slots are made in the piercer e for the reception of the said screws, so that the piercer may be adjusted upon the lever for piercing the material to the desired extent. The rear slotted end of the lever 2 is fitted in the fork 1 of the frame of the machine, and works upon the pin 2^a , so that the said lever is free to move both vertically and horizontally at its jointed end. The upward movement of the lever 2 is effected by the cam 3, and its forward horizontal motion by the cam 4. The return backward and downward motions of the lever are

produced by the action of the spring 5, one arm of which bears against the projecting part 65 2^b on the lever 2, and the other arm bears against the fixed part 1 of the machine. b is the shuttle-box, and f the needle-groove.

Instead of making the under piercer and feeder of a flat plate pointed at its acting end, 70 the said under piercer and feeder may be made of cylindrical or other shaped steel or other wire, as illustrated in Fig. 6, the acting end of this piercer being pointed. The wire from which the piercer and feeder, Fig. 6, is made is of such a thickness that the said piercer and feeder will move freely in the needle-groove f . The said piercer is marked e , and is fixed in the holder g by the screw h , as described with respect to the plate piercer and feeder. 80

My improved piercer and feeder may be applied to lock-stitch sewing-machines of different construction from those described and represented in the drawings.

I am aware that the awl of a wax-thread 85 sewing-machine has heretofore been combined with mechanism to reciprocate the awl both vertically and horizontally, and such, therefore, I do not broadly claim.

Having now particularly described and ascertained the nature of my said invention and in what manner the same is to be performed, I declare that what I claim is—

1. The combination, in a sewing-machine, of the shuttle-box b , having the needle-plate provided with the vertical needle-groove f , the awl e , moving in said groove, the horizontally-reciprocating lever pivoted to swing upward and downward, and connected with the awl, the cams, and a spring for imparting the said reciprocating and swinging movements to the awl, and the needle c , arranged above the shuttle-box, substantially as described. 95

2. The combination, in a sewing-machine, of the shuttle-box b , the needle c , arranged above the same, the awl e , the horizontally-reciprocating lever connected with the awl, and arranged below the shuttle-box, and pivoted to swing upward and downward, and the cams, and a spring for imparting the said reciprocating and swinging movements to the lever, substantially as described. 105

3. In a lock-stitch sewing-machine, the combination of the horizontally-movable slide-plate, the oscillating lever, the vertical post, and movable awl-carrier fitted therein, the cam mechanism for reciprocating the slide-plate and operating the awl-carrier, and the spring for returning the slide-plate to its normal position, with the grooved shuttle-box and the needle arranged above the same, substantially as described. 115
